Walter H. Meyer,
INVENTOR

or Mr. Max. Arnall,

ATTORNEY

UNITED STATES PATENT OFFICE.

WALTER H. MEYER, OF WASHINGTON, DISTRICT OF COLUMBIA.

VELOCIPED.

Application filed August 16, 1923. Serial No. 657,805.

To all whom it may concern:

Be it known that I, WALTER H. MEYER, a citizen of the United States, and residing at 1439 Massachusetts Ave. NW, Washington, 5 ton, in the District of Columbia, have invented certain new and useful Improvements in Velocipedes, of which the following is a specification.

This invention relates to amusement devices, particularly to wheeled toy vehicles, and has for its object the provision of a novel jointed vehicle formed as the representation of a horse or other animal and provided with means whereby propulsion 10 may be effected, the arrangement and construction being such that the device will have the appearance of a galloping horse, the action being very realistic and giving the rider, to a certain extent, the sensation 15 of riding upon such an animal.

An important and more specific object is the provision of a novel propelling means which is operable both by hand and foot, this means also acting to accomplish 20 steering.

An additional object is the provision of a vehicle of this type which will be simple 25 and inexpensive in manufacture, efficient and entertaining in use, conducive to health 30 by giving proper exercise, durable in service, and a general improvement in the art.

With the above and other objects and advantages in view, the invention consists in the combination and arrangement of the 35 several parts to be hereinafter more fully described and claimed and illustrated in the accompanying drawings in which:

Figure 1 is a side elevation of the device showing it in one position.

Figure 2 is a similar view showing the parts at the other limit of their movement.

Figure 3 is a top plan view.

Figure 4 is a rear elevation.

Referring more particularly to the drawings, the numeral 10 designates, broadly, the body of the device which is formed in the present instance to represent a horse but which might of course simulate any other animal. This body is formed of two 45 sections 11 and 12 hingedly connected at 13. The forward section 11 is formed as the head, neck and fore-legs of the animal, while the rear section 12 is formed as the 50 hind quarters. The rear section 12 carries

a suitable seat or saddle 15, and is preferably provided with a tail 16 to make the figure realistic, and the forward section may have a mane and bridle painted or otherwise provided thereon to improve the appearance and heighten the attractiveness 55 to the youthful mind.

Secured to the rear section 12 of the body and extending a distance beyond the hinge 13 and engaging the head section 11, there is provided two plates 11^a and 12^a, respectively, the purpose of which is to prevent lateral movement between the head section 11 and tail section 12, and to also prevent the gripping of the rider's person or clothing between the respective sections. 60

The hind legs 17 are provided with suitable bearings for the rear axle 18 which carries ground engaging wheels 19 and which has its intermediate portion formed with a crank 20. The wheels are here disclosed as being of the disk type and may in actual practice be simply wooden disks such as are used on certain styles of toy vehicles in popular use, though, if preferred, the wheels might just as well be 65 of the rubber-tired spoke type, such as are used on velocipedes and the like, such details being immaterial.

Rotatable through the rear portion of the front section 11 of the body is an inclined upright post 21 restrained against longitudinal movement by collars 22 and 23 which engage against the upper and lower edges of the front section 11, respectively. The upper end of this post carries a handle 24, while the lower end terminates in a fork 25 within which is journaled the front wheels 26. The rear edge of the head section 11 is inclined downwardly and outwardly, as indicated at 11', and is provided at the bottom thereof with an extension 11'', the purpose of which will be hereinafter described. The front edge of the rear section is inclined downwardly and inwardly as indicated at 12', and is provided with a shouldered recess 12'' for engagement with the extension 11'' on the head section 11. The purpose of these arrangements is to provide against collapsing 90 of the parts while the rider is mounting, and to absorb the shocks while in operation. Secured upon opposite sides of the front legs are foot rests 27 which may be 95 100 105

used in conjunction with the handle 24 for effecting propulsion. Engaged upon the crank 20 is a forwardly extending link 28 which has its forward end laterally deflected at 29 and rotatably engaged through the front legs, withdrawal being prevented by means of a cotter pin 30 or other equivalent means.

As shown in Fig. 1 of the drawings, the parts are in the inoperative position, the position of the front wheel 26 being slightly to the rear of the hinge 13, the faces 11' and 12', and the extension 11'' and recess 12'' of the sections 11 and 12, being in contacting engagement.

In operating the device a child seats himself upon the saddle 15, grasps the handle 24 and rests his feet upon the foot rests 27. By pushing forwardly with the feet and at the same time drawing back on the handle, it is apparent that the two sections of the horse will be swung relatively far apart on the hinge 13, as shown in Fig. 2, the distance between the front and rear wheels then increasing. After the handle is pulled back, it is then pushed forwardly which will result in swinging the sections together again. This action is continued and it is, of course, apparent that the link 28 engaged upon the crank 20 will operate to turn the rear axle 18 which carries the rear wheels so that the device will be propelled along the ground or other surface. To effect steering it is merely necessary to turn the post 21, and consequently the wheel 26, by turning the handle 24 in one direction or the other, this steering action not interfering in any way with the propulsion.

From the foregoing description and a study of the drawings it will be apparent that I have thus provided a simply constructed and easily manipulated toy vehicle which will be most entertaining and amusing in use on account of its life-like movements which are well calculated to simulate those of a horse or other animal. It is evident that the device may be constructed at small cost and it is also apparent that, owing to the fewness of the parts, that there is very little to get out of order so that it should have a long life and satisfactorily perform all of its functions.

While I have shown and described the preferred embodiment of my invention, it is, of course, to be understood that I reserve the right to make such changes in the form, construction and arrangement of parts as will not depart from the spirit of the invention or the scope of the subjoined claims.

Having thus described my invention, what I claim as new and desire to secure by Letters Patent, is:

1. A device of the character described comprising a jointed body including front and rear sections, an axle carried by the

rear section and provided with ground engaging wheels and a crank, a link pivotally connected with said crank and with the lower end of said front section, and a post journaled through the front section and provided at its lower end with a front wheel and at its upper end with a controlling handle.

2. A device of the character described comprising a jointed body including front and rear sections, an axle carried by the rear section and provided with ground engaging wheels and a crank, a link pivotally connected with said crank and with the lower end of said front section, a post journaled through the front section and provided at its lower end with a front wheel and at its upper end with a controlling handle, and means forming part of said rear section for holding the jointed sections against lateral movement.

3. A device of the character described comprising a jointed body including front and rear sections, an axle carried by the rear section and provided with ground engaging wheels and a crank, a link pivotally connected with said crank and with the lower end of said front section, a post journaled through the front section and provided at its lower end with a front wheel and at its upper end with a controlling handle, and foot rests projecting laterally from the lower portion of the front section.

4. A device of the character described comprising a body including front and rear sections hingedly connected at their upper edges, the body being formed to simulate an animal and including front and rear legs on the respective sections, and an axle carried by the rear legs and equipped with ground engaging wheels, a crank on said axle, a link pivotally connected with the crank and with the front legs, a post journaled through the front section and carrying a handle, foot rests projecting from the sides of the front section, a front wheel journaled on the lower end of said post, and means for holding the jointed sections against lateral movement.

5. A device of the character described comprising a body formed of front and rear sections hingedly connected at their upper edges, plates secured to one of said sections for preventing lateral movement between the said sections, an axle journaled through the rear section and carrying ground engaging wheels, said axle being formed with a crank, a link pivotally connected with said crank and with the front section, a dirigible wheel carried by the front section, and means carried by the front section whereby to effect steering, said means being connected with the said dirigible wheel.

6. A device of the character described comprising a body formed of front and rear sections hingedly connected at their

upper edges, devices associated with the said sections for preventing lateral movement between the said sections, an axle journalled through the rear section and carrying ground engaging wheels said axle being provided with a crank, a link pivotally connected with said crank and with the front

section, a dirigible wheel carried by the front section and means carried by the front section whereby to effect propulsion, said means being connected to said dirigible wheel.

In testimony whereof I affix my signature.

WALTER H. MEYER.
